Specification for Design.

Patented Nov. 15, 1921.

Application filed November 15, 1920. Serial No. 424,303. Term of patent 7 years.

To all whom it may concern:

Be it known that I, WILLIAM L. SIX, a citizen of the United States, residing at Kansas City, in the county of Jackson and State of Missouri, have invented a new, original, and ornamental Design for a Finned Tubular-Boiler Unit, of which the following is a specification, reference being had to the accompanying drawing, forming a part thereof.

In the drawing:—

Figure 1, represents a top plan view of a

finned tubular boiler unit embodying my improved design.

Fig. 2, is a vertical longitudinal section of said unit.

Fig. 3 is a vertical transverse section of said unit.

I claim:—

The ornamental design for a finned tubular boiler unit, as shown.

WILLIAM L. SIX.
